UNITED STATES PATENT OFFICE.

BERT W. KING, OF DETROIT, MICHIGAN, ASSIGNOR TO BARNES SCALE COMPANY, OF DETROIT, MICHIGAN, A CORPORATION OF MICHIGAN.

V-BEARING FOR WEIGHING SCALES.

1,426,393.

Specification of Letters Patent. Patented Aug. 22, 1922.

Application filed May 18, 1921. Serial No. 470,621.

To all whom it may concern:

Be it known that I, BERT W. KING, a citizen of the United States, residing at Detroit, in the county of Wayne and State 5 of Michigan, have invented certain new and useful Improvements in V-Bearings for Weighing Scales, of which the following is a specification.

This invention relates to V groove bearings for weighing-scales. These V groove bearings are usually agate blocks with a V groove in the top. It is the object of the present invention to provide a bearing which is not only self-aligning but which 10 will adjust itself to bring the V groove bottom into line to line engagement with the knife edge instead of a one point engagement. This construction is especially designed for use with a double knife edge bearing such as shown in the drawings. 15 In a double knife edge bearing the knife edge cannot climb in its bearing and jump over the agate block. In the ordinary agate V groove block which is cemented into the 20 post recess, when the cement dries the V groove bottom often sags or draws angularly away from the knife edge, leaving a one point bearing for the knife. With this one 25 point bearing the load will quickly wear into the agate block. This difficulty is obviated in my improved bearing which has 30 the adaptability within small limits of not only adjusting itself on a vertical axis to the knife edge but also the capacity of turning with respect to the knife edge upon a 35 horizontal axis.

In the drawings,—

Fig. 1 is an elevation of an end of the scale-operating levers and support in an 40 automatic computing scale. This happens to be the end remote from the pedestal.

Fig. 2 is an end elevation of the fulcrum support for the lever.

Fig. 3 is a plan view of the cradle that 45 holds the V groove block.

Fig. 4 is a perspective of the same.

a designates a scale lever. The part shown in Fig. 1 is the cross bar portion that connects the yoke arms of the lever. One of 50 the arms is shown in Fig. 2 and is designated b. This lever chances to be what I term a drum-actuating lever of the character described in my prior applications #381,246 and #432,808. However, the bearing can 55 be used on any one of a number of levers that

are used in the different styles of scales so I do not wish to limit myself to any particular location of the bearing.

c designates a cradle for fulcruming this lever. This cradle is adjustable vertically 60 by the screws d. This cradle is provided with an upright e having a suitable recess in its top to receive the V groove block. This recess forms posts at the side of the recess in the upright and these posts receive 65 the set screws or pins f. The set screws or pins screw into the posts and pass through the bearing cradle g which is simply a stamping having two large ears h, h and two small ears j turned up. The bottom of 70 the stamping is provided with a central cross rib i. The set screws or pins run through the perforations k in the large ears h and bear directly against the agate block l. When these screws are screwed against 75 the block the knife edge resting within the groove of the block, this block will swing around on a vertical axis and align itself to the knife. The amount of twisting movement required is very small—about 3-4 80 thousandths of an inch and hence the block will twist in between the points of the screws or pins this small amount.

The screw points hold the block which 85 rocks on the round rib i in the bottom of the cradle. This permits the V groove block to align itself by rotation in a vertical plane on an axis perpendicular or transverse to the plane of the knife edge and thereby cause the bottom of the groove to contact with the 90 knife edge in line to line engagement. A bearing of this kind would be of little value unless there is some positive device for locking the knife edge in the V block so it cannot jump up over the edge of the block and become wedged into the recesses m between the block and the side ears h of the cradle. Such climbing of the bearing is prevented by the double knife edge arrangement. The knife edge n points upwardly and is in accurate 100 alignment with the knife edge o which points downwardly. The bar p is clamped down on the upwardly-facing knife edge by the screw q so that the knife edge o cannot rise out of the V block.

The cradle g preferably hangs suspended from the pins f and spaced from the bottom of the recess so it too has a freedom of movement to facilitate the V groove bottom lining up with the knife edge.

105

110

I am not the first one to fulcrum a lever upon a floating bearing as loops have been used in heavy duty scales to support the knife edges but I do believe that no one here-
5 tofore has supported a V block to rock and twist in the manner that I have indicated.

It will be noticed that the pivots support the block in spaced relation with respect to the side wall of the cradle and hence permit
10 it to twist on a vertical axis and rock on a horizontal axis. This spacing is referred to in some of the claims as a block supported in isolated relation.

What I claim is:

15 1. A bearing for the purpose specified, having in combination with a knife edge, a V groove block, a pair of set screws and a support through which said set screws are adjustable to engage with the V groove block
20 and to support the V groove block to rock on an axis perpendicular to the knife edge.

25 2. A bearing for the purpose specified, having in combination with a knife edge, a V groove block, set screws for bearing against the side of the V groove block, and a cradle in the form of a stamping having a rib stamped in its bottom and ears turned up at the sides for engaging loosely about the block, said block being thereby supported to rock on an axis transverse of the knife edge.

3. In a bearing for the purpose specified, the combination of a double knife edge with aligned downwardly and upwardly-pointed knife edges so that the two knife edges have 35 a common axis of rotation, a fixed member on the scale engaging against the upwardly-pointing knife edge to lock the downwardly-directed knife edge in its bearing, a V groove block acting as the bearing for the 40 downwardly-directed knife edge, and means for supporting said V groove block to float.

4. A bearing for the purpose specified, having in combination with a knife edge, a V groove block, pins with ends engaging 45 opposite points on the sides of the V groove block, and a cradle hung from said pins and provided on its bottom with a portion on which the V groove block may rock.

5. A bearing for the purpose specified, 50 having in combination with a knife edge, a V groove block, pins with ends for bearing at opposite points on the sides of the V groove block, and a cradle in the form of a stamping having perforated ears through 55 which the said pins pass and which serves to hang the cradle upon the pins, said cradle being provided with a rib in its bottom on which the said block may rock.

In testimony whereof I affix my signature. 60

BERT W. KING.
